UNITED STATES PATENT OFFICE.

WILLIAM H. CATER, OF CHICAGO, ILLINOIS.

FILTER FOR WELL SCREENS.

Application filed April 27, 1925. Serial No. 26,172.

In wells having reticulated or apertured casings or screens, it is frequently desired or required to provide them with external, enclosing filters to assure the purity of the 5 water or other liquid supply which finds its way through the casing into its interior.

I have discovered that carborundum or its equivalent is a particularly appropriate, effective and efficient means for accomplishing 10 this function and the present invention comprises also the employment of such a filter to assist by its weight in causing the descent of the foraminous casing during the sinking of the latter in the ground.

Accordingly, in the preferred embodiment 15 of the invention, the shoe or foot at the bottom of the casing, which cuts its way through the earth, is so formed that the carborundum filter, preferably made in arcuate sections designed to rest on one another and form a series of superposed rings 20 or cylinders, will impose its weight thereon to help force the shoe and its associated casing downwardly.

As the casing or screen descends new sections or layers of the encasing filter are applied to the lower layers thereof and thus 25 the filter as a whole is built up or formed progressively during the well sinking operation.

To permit those trained in this art to fully understand this invention and its various advantages, I have illustrated the same in the accompanying drawing which forms a 35 part of this specification and throughout the views of which like reference characters have been employed to designate the same parts.

In this drawing: 40 Figure 1 is a fragmentary vertical sectional view of a well undergoing the sinking operation or it may be considered an illustration of the lower portion only of a completed well;

Figure 2 is a plan view of one of the filter rings composed of interfitted arcuate sections, the ends of which are locked together; and

Figure 3 is a similar view of a somewhat 50 modified form of filter element.

By reference to this drawing, it will be seen that the usual or customary apertured or perforated cylindrical well casing or screen 11 has a sharp-edged round foot 12 somewhat larger in diameter than the casing and which cuts or forces its way down-

wardly through the earth during the well sinking or driving operation, it being understood that the casing or screen is made of sections or parts which are coupled together 60 lengthwise in the usual way as the well increases in depth, new sections being added at the top as is customary in operations of this kind.

The dirt or ground inside of the casing is 65 removed during the driving operation by means of a pump, not shown, in accordance with the conventional practice and in this way the casing gradually sinks down into the ground, its contents being removed as it 70 proceeds.

It is necessary to weight the casing to cause its descent and accordingly the foot or shoe is supplied with an outstanding shoulder 13 on which the sectional car- 75 borundum filter 14 rests.

Each of the superposed layers or rings of the filter is preferably made of a plurality of arcuate or curved parts or sections 15 unitedly or conjointly forming a complete 80 ring as is fully illustrated.

In order that the ends of such filter sections may be maintained in proper register and correct alignment, one end of each section is provided with a groove or recess 16 85 adapted to receive a correspondingly-shaped tongue or lug 17 on the end of the adjacent or adjoining section, all as is clearly shown in Figure 2.

The lower layer or ring section of the filter rests or bears directly on the casing foot 90 as is clearly depicted, and as the well sinking operation proceeds, other filter sections or layers or rings are applied around the casing on top of those already fitted thereto, 95 whereby their combined weight is employed to assist in driving or forcing the shoe and associated perforated casing downwardly into the earth.

When the casing reaches its proper depth, 100 it will have been permanently encased or enclosed in a sectional or divided carborundum filter which seems to possess especially good filtering characteristics in relations of this character.

That is to say, carborundum performs the filtering operation efficiently and without becoming unduly clogged by particles of the surrounding earth becoming embedded therein.

It is not always necessary to form the ends of the curved filter sections with interlock-

ing or intermatching features and such a filter 18 with plain ends is illustrated in plan in Figure 3.

The invention is not necessarily limited 5 and restricted to the precise and exact details of structure shown and described and these may be modified within comparatively wide limits without departure from the heart and essence of the invention and without the sacrifice of any of its material benefits and advantages, the invention residing 10 not only in the finished well but also in the method employed of sinking or driving the same wherein the weight of the filter is used 15 to force the foot into the ground.

I claim:

1. The method of sinking a perforated single-wall sheet-metal well-casing having a lower foot of larger external diameter than 20 that of the main body of the casing, consisting in forcing said casing downwardly into the earth progressively and assisting such descent by imposing on the exposed portion of such foot the gradually increasing 25 weight of a filter enclosing the casing whose height is progressively increased by the addition thereto of successive superposed sections, each comprising a plurality of arcuate contacting filter elements unitedly forming 30 such section.

2. The method of sinking a perforated single-wall sheet-metal well-casing having a lower foot of larger external diameter than that of the main body of the casing, consisting 35 in gradually forcing said casing downwardly into the earth and assisting such descent by imposing on the exposed portion of such foot the progressively increasing weight of a gradually elongating filter en-

closing the casing, whose height and weight 40 is progressively augmented by building up successive superposed sections thereof, each such section being composed of a plurality of arcuate parts interlocking directly together and unitedly forming such sections. 45

3. In a well construction of the character described, the combination of a perforated single-wall sheet-metal well-casing having a foot of larger external diameter than that of the main body of the casing, and a carborundum filter enclosing this casing and resting 50 on the outer exposed portion of said foot and composed solely of a plurality of superposed annular carborundum filter sections.

4. In a well construction of the character 55 described, the combination of a perforated single-wall sheet-metal well-casing having a foot of larger external diameter than that of the main body of the casing, and a filter enclosing this casing and resting on the outer 60 exposed portion of said foot, said filter comprising superposed sections each of which is composed solely of several contacting filter elements conjointly forming the section.

5. In a well construction of the character 65 described, the combination of a perforated single-wall sheet-metal well-casing having a foot of larger external diameter than that of the main body of the casing, and a carborundum filter enclosing such casing and resting 70 on the exposed portion of said foot, said filter comprising superposed sections each of which is composed solely of several arcuate carborundum filter parts conjointly forming 75 the section.

In witness whereof I have hereunto set my hand.

WILLIAM H. CATER.
